UNITED STATES PATENT OFFICE

115,275

DESIGN FOR TEXTILE FABRIC

Jack Rubin, New York, N. Y.

Application April 19, 1939, Serial No. 84,403

Term of patent 3½ years

To all whom it may concern:

Be it known that Jack Rubin, a citizen of the United States and resident of New York city, in the county of New York, State of New York, has invented a new, original, and ornamental Design for Textile Fabric, of which the following is a specification, reference being had to the accompanying drawing forming part thereof, and in which,

The single figure of the drawing illustrates the textile fabric embodying my new design.

I claim:

The ornamental design for textile fabric, substantially as shown.

JACK RUBIN.
